UNITED STATES PATENT OFFICE

FRANK E. BAKER, OF SYRACUSE, NEW YORK, ASSIGNOR OF ONE-HALF TO LOUIS WILL,
OF SYRACUSE, NEW YORK

IRONING PRESS

Application filed May 31, 1929. Serial No. 367,380.

This invention relates to an ironing press involving the use of a substantially horizontal stationary buck and a heated press head yieldingly mounted upon a carriage which in 5 turn is movable transversely of the buck for moving the press head to and from a position directly over the buck in combination with means operable at will for moving the press head into pressing co-action with the buck.

10 The main object is to provide a simple and comparatively inexpensive ironing press for domestic or household use whereby practically all kinds of laundered or dried fabrics may be more conveniently and expeditiously ironed and dried, than has heretofore been practiced, without in any way injuring the articles operated upon.

15 In other words, I have sought to provide means whereby the usual domestic ironing may be accomplished by direct pressure as distinguished from the rotary or mangle-type and sad-iron type of ironing machine, so that the finest or coarsest fabrics may be efficiently ironed without liability of injury.

20 Another object is to enable the ironing head to be moved by hand to and from its pressing position so that the amount of pressure or power may be regulated entirely by the operator according to the nature of the fabric operated upon.

25 One of the specific objects is to mount the ironing head upon a carriage which is movable along a suitable track transversely of the buck so that when the carriage is in its rear-most position the entire upper surface and marginal edges of the buck will be exposed for the reception of the fabrics to be ironed without, in any way, interfering with the ironing head or other parts of the machine.

30 Another specific object is to provide resilient connections between the ironing head and carriage whereby the head will be yieldingly held in spaced relation to the buck when the carriage is moved forwardly to bring the head directly over the buck and also to enable the head to be forced to its pressing position against the action of said resilient connections by the simple operation of a cam lever under 35 the control of the operator thereby rendering

the operation of the machine entirely safe in the hands of a skilled or unskilled operator.

Another object is to require the use of both hands in the adjustments of the carriage and ironing head to further reduce the liability of 55 injury of the hands by burning or pressure between the press elements.

Other objects and uses relating to specific parts of the machine will be brought out in the following description.

60 In the drawings:—

Figure —1— is a top plan of an ironing press embodying the various features of my invention.

Figure —2— is a front elevation of the 65 same together with the upper portion of a cabinet or supporting frame upon which the machine is mounted.

Figure —3— is an enlarged vertical sectional view taken in the plane of line —3—, 70 Fig. 2, the dotted line indicating the inactive position of the carriage and press head mounted thereon.

Figure —4— is an enlarged horizontal sectional view taken in the plane of line 4—4, 75 Fig. 2, showing more particularly the arrangement of the electric heater coils.

Figure —5— is a horizontal sectional view taken in the plane of line 5—5, Fig. 3.

Figure —6— is an enlarged detail sectional 80 view taken in the plane of line 6—6, Fig. 5.

Figure —7— is an enlarged transverse vertical sectional view taken in the plane of line 7—7, Fig. 2, except that the ironing head is shown in pressing co-action with the buck, 85 the dotted lines indicating the elevated position of the head and its supporting springs and also the transverse movement of the ironing head when in its pressing position.

Figure —8— is an enlarged end view of 90 the upper portion of the buck and ironing head and the overlying portion of the carriage and head supporting means showing the effect of the operation of the cam lever upon the head as the latter is brought to its 95 pressing position.

This machine is adapted to be mounted upon any suitable table, shelf or cabinet —A— and comprises a main supporting frame —1— having parallel supporting tracks or 100

rails —2— and upright frames or standards —3— for receiving and supporting a horizontal, elongated buck —4— of wood or other suitable material having a padded covering —5—.

5 A U-shaped carriage —6— has its lower side mounted upon the track or guide rails —2— for movement along the track and its upper side operatively extended over the top of the buck in spaced relation thereto for receiving and supporting an ironing head —7— which is yieldingly mounted upon the upper side of the carriage for relatively vertical movement by means of a pair of springs —8— and suspension bolts —9— and is adapted to be moved to its pressing position by means of a cam lever —10—, as shown more clearly in Figs. 3, 7, and 8.

20 The cabinet —A— is provided with a central leg or foot opening —a— therethrough from front to rear to permit the operator to stand or sit in close relation to the machine and is also provided with a plurality of drawers —a'— for the reception of the ironed or unironed articles, the top of the table being mainly horizontal for receiving and supporting the frame —1— of the machine in a similar position.

30 The track rails —2— forming the base of the frame —1— are arranged in parallel spaced relation transversely of and some distance below the buck —4— and are preferably made of channel irons arranged with their channels facing each other, the major positions of the rails from front to rear being disposed in a horizontal plane while the rear positions are deflected downwardly at 2° in inclined planes to cause a corresponding tilting movement of the carriage —6— 40 when the latter is moved to its extreme rearward position, the opposite ends of the channels in the rails —2— being closed to form limiting stops —11— and —12—, as shown more clearly in Figures 3 and 5, respectively.

45 The upright frames or standards —3— are bolted or otherwise secured to the upper edges and outer sides of the rails —2—, as shown more clearly in Fig. 2, to extend upwardly some distance above said rails for receiving and supporting the buck —4— on the upper edges thereof, as shown more clearly in Fig. 3, said frames being provided with lower and upper lengthwise bars —13— and —13'—, the lower bars —13— being disposed in a plane directly over and in close proximity to the upper edges of the horizontal portions of the rails —2— for receiving and supporting a shelf —14—, as shown in Fig. 3.

55 The buck —4— is supported directly upon the top bars —13'— of the standards —3— and is preferably elongated laterally so as to afford a relatively large area for supporting the articles to be ironed, the pad —5— being drawn downwardly around the mar-

ginal edges of the buck and secured at the under side thereof by shirring cords —5'—, Fig. 3.

60 The carriage —6— comprises in this instance of a pair of U-shaped bars —6'— arranged edgewise vertically and having their lower arms overlapping upon the inner channel sides of the guide rails —2— below the buck and their upper arms adapted to overlie the upper surface of the buck in considerably spaced relation thereto when the carriage is moved to its operative position for receiving and supporting the head —7— between the upper arms and upper surface of the buck, Fig. 3.

65 The intermediate portions of the lower arms of the U-shaped bars —6'— of the carriage are rigidly connected to each other by a cross bar —15— to hold them in parallel spaced relation, the front ends of the upper horizontal portions of the bars —6'— being connected by a cross rod —16— carrying a suitable handle —17— which together with the rod —16— serves to hold the upper portions of the carriage bars —6'— in parallel spaced relation and also serves as a means by which the carriage may be moved back and forth along the track rails —2—.

70 The lower horizontal arms of the carriage bars —6'— are also connected by additional cross bars —18— and —19— arranged in parallel spaced relation at opposite sides of and some distance from the cross bars —15—, as shown more clearly in Fig. 5.

75 These cross bars —18— and —19— extend beyond the outer faces of the lower arms of the carriage bars —6'— and into the channels in the adjacent sides of the track rails —2— for receiving rollers —20— which are adapted to ride upon the lower walls of the channels of said track rails and may also contact with the upper walls of the same channel to guide the carriage along the track in a plane substantially parallel with all portions thereof except for a slight tilting movement of the carriage as will be hereinafter more fully explained.

80 The springs —8— are preferably of the single flat leaf type extending lengthwise of the upper arms of the carriage —6— and having their rear ends secured by suitable anchor pins —21— to the outer sides of the bars —6'— near the rear ends of the upper horizontal portions of said bars, as shown in Fig. 3.

85 The portions of the springs —8— just immediately in front of the anchoring pins —21— are engaged with underlying bearing pins or fulera —22— some distance to the rear of the suspension bolts —9— so that the front ends of the springs may be free to yield vertically for establishing a correspondingly resilient connection between the head —7— and carriage —6—.

90 That is, the front ends of the springs —8—

extend over the central portion of the head —7— outside the opposite bars —6— of the carriage so that the head and its connecting bolts —9— carried by the free ends of the springs —8— may have free vertical movement relatively to the carriage for permitting movement of the head —7— into and out of pressing co-action with the buck —4— when the carriage with the head thereon is moved to its pressing position.

Each spring —8— is adapted to receive and support a pair of the head-supporting bolts —9— which are located at opposite sides of the longitudinal center of the head —7— and have their lower ends rigidly secured to said head, as shown in Fig. 7.

The upper ends of the bolts —9— are passed through elongated openings —24— in the adjacent springs —8— and are provided with nuts —25— for engaging the upper surface of the springs for returning the head —7— to its uppermost position when released by proper adjustment of its cam lever —10—.

A bearing plate —23— is secured to the upper surface of the ironing head —7— and is provided with threaded apertures for receiving the lower ends of the bolts —9— which are screwed into threaded apertures in the head —7— and serve to hold the bearing plate —23— in its operative position.

The cam lever —10— comprises a substantially rectangular cam bar —10'— and a handle —10"— secured thereto to project upwardly and forwardly therefrom when in its inoperative position, as shown in Fig. 3.

This cam bar —10'— extends lengthwise of the press head —7— near the longitudinal center thereof and between the bolts —9— of each pair and is adapted to be moved from a horizontal position, shown in Fig. 3, to a substantially vertical position, shown in Fig. 7, for effecting the operation of the press head —7— from its normal inoperative position to its pressing position.

That is, when the cam bar —10'— is adjusted to its horizontal position, the springs —8— will elevate the press head —7— and yieldingly hold the same in its elevated position with the cam bar —10'— flatwise or horizontal between the bearing plate —23— and underside of the upper horizontal portions of the carriage —6—.

On the other hand, when the cam plate —10'— is rocked by its handle —10"— from its normal position, shown in Fig. 3, to its vertical position, shown in Fig. 7, the press head —7— will be depressed into pressing co-action with the upper surface with the buck —4— and the arms —6— will be placed under more or less tension.

When the cam plate —10'— is rocked from its horizontal position to its vertical position its lower edge will be engaged in a notch —23"— in the upper surface of the plate —23— to hold the lower edge of the cam

plate against sliding movement on the bearing plate.

The rearward movement of the upper edge of the cam bar —10'— is limited by a stop shoulder —26— on the lower edges of the overlying arms of the carriage —6—, as shown in Figs. 7 and 8.

It is sometimes desirable to move the press head —7— forwardly and rearwardly relatively to the buck —4— when the head is in its pressing position for the purpose of polishing the articles under treatment, such as cuffs, collars, shirt bosoms and the like, and for this purpose, a locking dog —27— is pivoted at —28— to the upper portion of the carriage —6— to move into and out of engagement with the front face of the upper edge of the cam plate —10'— when the latter is adjusted to its vertical position, as shown in Fig. 7.

It is now evident that when the locking dog —27— is adjusted to its holding position, it together with shoulder —26— will hold the upper edge of the cam bar —10'— against forward and rearward movement relatively to the carriage —6— while the lower edge of the cam bar will be in engagement with the front and rear walls of the groove —23"— in the bearing plate —23—.

It, therefore, follows that if the cam plate —10'— is rocked forwardly and rearwardly by its handle —10"—, the lower edge of the cam bar —10'— will be similarly oscillated for transmitting a corresponding forward and rearward movement to the head —7—.

Under ordinary pressing conditions, however, the dog —27— will be thrown by hand from its holding position to the position shown by dotted lines in Fig. 7 to rest against a limited stop pin —30— thus permitting the rocking movement of the cam plate —10'— from one extreme position to the other without reciprocating the head forwardly and rearwardly as may be required for closing and opening the press head —7— for direct pressure.

The cam plate —10'— is held against endwise displacement by suitable stop plates —31— which are bolted or otherwise secured to opposite ends of the bearing plate —23— to extend across the adjacent portions of the ends of the cam plate, as shown in Fig. 8.

The press head —7— is preferably made of cast aluminum or other suitable metal having a relatively high degree of heat conductivity and is provided in its upper side with a heating chamber —32— for receiving an electrical resistance coil —33— which in this instance is enclosed within but insulated from an outer tube —34— of copper or equivalent metal of relatively high degree of heat conductivity.

This pipe with the resistance coil therein is preferably extended back and forth longitudinally of and within the heating chamber

—32— throughout the major portion of said chamber with suitable return bends at the ends for continuity of transmission of the current and heat radiation throughout the 5 chamber.

These heating elements are arranged in heat transfer relation to the bottom portion of the head —7— for heating the same to a relatively high degree of temperature within 10 a comparatively short time and with a minimum amount of current.

The top of the heating chamber is closed by a layer —35— of asbestos or equivalent 15 heat insulating material and an upper plate —36— of metal which is bolted or otherwise secured to the marginal walls of the heating chamber —32— to serve the double purpose of retaining the heating unit in the chamber and also for reducing the heat radiation from 20 the top of the chamber.

An electrothermostatic switch —33'—, Figure 4, is connected in the heater circuit within the heating chamber —32— for automatically breaking the circuit in case of excessive 25 temperature of the heater as a safety factor against fire which might result from over-heating.

The ends of the heater coil are connected to suitable terminals or binding posts —33"— which in turn may be connected to any available 30 source of current supply.

Suitable means is provided for adjusting the carriage —6— with the head —7— thereon toward and from the buck independently 35 of the cam lever —10— to compensate for varying thicknesses of the material operated upon and for this purpose the cross shaft —19— is provided with a pair of cams or eccentrics —37—, Figures 3, 5 and 6, adjacent 40 the inner faces of the lower arms of the U-shaped carriage bars —6'— which in turn are provided with lower and upper shoulders —38— engaging the lower and upper faces of the adjacent cams —37— whereby the rotation 45 of the shaft —19— with the cams —37— thereon will tilt the carriage vertically about the axis of the cross shaft or rod —18— and thus effect a corresponding adjustment of the ironing head —7— toward or 50 from the upper surface of the buck when the carriage is in its pressing position.

If desired, the cam shaft —19— may be locked in its different positions of adjustment by means of a locking bolt —39— which is normally spring pressed into engagement with one or the other of a series of sockets —40— in the periphery of one of the cams —37—, as shown more clearly in Figs. 5 and 55 6, it being understood that the lower arms of the carriage will be provided with vertically elongated slots —41— for receiving the adjacent portions of the shaft —19— and permitting the tilting movement of the carriage in the manner described.

60 The intermediate portion of the cross shaft

—19— is provided with a handle —19'— by which it may be turned for effecting the vertical tilting movement of the carriage.

If desired, the table —14— may be provided with an upwardly curved deflecting 70 plate —42— of sheet metal or equivalent material for deflecting the articles to be ironed downwardly on to the upper surface of the table —14— thereby to avoid the contact of the articles with the rear portion of the carriage. (See Fig. 3.)

Operation

Assuming that the carriage —6— is in its extreme rearward position, as shown by 80 dotted line in Fig. 3, and that it is desired to iron various fabrics, the article to be ironed will then be placed upon the upper surface of the buck —4— and smoothed out by hand in the usual manner after which the carriage —6— with the heated head —7— thereon will be drawn forwardly along the track —2— by means of the handle —17— until the head is directly over the buck.

The carriage is then held in this position by 90 one hand while the cam lever —10— is being moved upwardly and rearwardly by the other hand thereby turning the cam bar —10'— from a horizontal position, shown in Fig. 3, to a vertical position, shown in Fig. 7, 95 for depressing the head —7— against the action of its supporting springs —8— into pressing co-action with the buck —4— aided by the more or less resilient action of the front ends of the upper arms of the carriage —6—.

This adjustment of the cam will automatically hold the press head in its pressing position for an indefinite period of time or until the article under treatment is thoroughly ironed and dried whereupon the cam lever —10— may be returned to its normal position to allow the head to be elevated by its supporting springs —8—.

This operation may be repeated upon different portions of the same article or upon different articles with the assurance that the garment can not be over-heated by reason of the automatic action of the thermostatic switch —33'—.

If more or less polishing of the article under treatment is required, the cam lever —10'— may be moved back and forth when the cam bar —10'— is brought to its vertical position for effecting a forward and rearward movement of the press head —7— upon the surface of the article while under more or less pressure.

During this latter operation, the degree of pressure of the press head upon the garment may be varied by simply turning the cam shaft —19— in one direction or the other which in turn will effect a correspondingly vertical movement of the press head toward and from the buck.

This latter adjustment may also be used, as may be required, for pressing articles of different thickness.

When the ironing operation upon each article is completed, the carriage—6—may be returned to its normal position to enable other articles to be readily placed over and upon the buck without liability of contact of the hands of the operator with the heated press head.

10 The purpose of the rearwardly and downwardly incline of the rear ends of the track—2—is to cause a downwardly tilting movement of the carriage when returned to its normal position and thereby to increase the space between the rear edge of the buck and front edge of the press head to a safe degree for the free manipulation of the articles over and upon the buck preparatory to ironing without liability of contact with the operator's hands with the heated head.

What I claim is:

1. In a pressing machine, a buck, two substantially U-shaped members spaced apart 25 and disposed with their leg portions substantially horizontal, one of the leg portions of each U-shaped member being below the buck and the other spaced above the buck, means connecting the U-shaped members for simultaneous movement transversely of the buck, spring arms having one of their ends mounted on respective upper leg portions of the U-shaped members and extending forwardly from their mountings, a press head 30 mounted on the front ends of said spring arms below the upper leg portions of the U-shaped members and movable with the connected U-shaped members to and from a position over the buck, and means for depressing the press head into pressing contact with the buck when registered therewith, against the supporting action of said arms.

2. In an ironing press, a buck, a track extending transversely across the under side of 45 the buck and having its rear end inclined downwardly, a carriage movable along the track, a press-head, mounted on the carriage to move therewith across the top of the buck, the movement of the carriage along the inclined portion of the track causing the carriage and head to tilt rearwardly and downwardly, and means for moving the head into pressing coaction with the buck when overlying the same.

55 3. In an ironing press, a buck, a stationary track extending transversely across the underside of the buck, a carriage movable along the track, means for fulcruming the carriage on the track for tilting movement relatively 60 to the track, a press head yieldingly mounted on the carriage and movable therewith across the top of the buck, and means for moving the press head into pressing co-action with the buck when overlying the same.

65 4. In a pressing machine, a buck, two sub-

stantially U-shaped members spaced apart and disposed with their leg portions substantially horizontal, one of the leg portions of each U-shaped member being below the buck and the other spaced above the buck, means connecting the U-shaped members for simultaneous movement transversely of the buck, spring arms having one of their ends mounted on respective upper leg portions of the U-shaped members and extending forwardly 70 from their mountings, a press head mounted on the front ends of said spring arms below the upper leg portions of the U-shaped members and movable with the connected U-shaped members to and from a position over the buck, and a hand-operated cam means movable between the upper legs of said U-shaped members and the press head for depressing the press head into pressing contact with the buck when registered therewith, 75 against the supporting action of said spring arms.

5. In an ironing press, a buck, a track extending transversely of and across the underside of the buck, a carriage movable along the track, an ironing head, springs on the carriage yieldingly supporting the head in spaced relation to the buck when the head overlies the buck, and means operable at will for moving the head into pressing co-action 90 with the buck against the action of said springs.

6. In an ironing press, a buck, a track extending across the underside of the buck, a carriage movable along the track and having a portion thereof movable to and from a position directly over the buck, springs mounted on the carriage to move therewith, an ironing head supported by said springs, and a flat cam-plate interposed between the head and 100 said portion of the carriage and turnable transversely at will for moving the head against the action of the spring into pressing co-action with the buck.

7. In an ironing press, a frame, a buck mounted on the frame, a track mounted on the frame and extending transversely of and beneath the buck, a carriage movable along the track and extended upwardly at the rear of and above the buck when in its pressing 110 position, springs mounted on the upper portion of the carriage, an ironing head suspended from said springs, and a hand-operated cam interposed between the head and upper portion of the carriage for moving the head 115 into pressing co-action with the buck.

8. In an ironing press having cooperative pressing elements of approximately equal pressing area and both elongated in one and the same direction, a carriage slidable transversely of the longer axis of said elements and having a portion thereof adapted to overhang said elements, springs for supporting one of the pressing elements on the carriage, and a cam-plate between the last-named 120 125 130

- pressing element and overhanging portion of the carriage and operable at will for forcing said last-named pressing element into pressing co-action with the other pressing element.
9. In an ironing press, a buck, a track extending transversely of the buck, a carriage movable along the track, an ironing head mounted on the carriage, means for moving the head relatively to the carriage into pressing co-action with the buck, and means for tilting the carriage relatively to the track for varying the pressing relation between the buck and head.
10. In an ironing press, a buck, a track extending transversely across the under side of the buck, a carriage movable along the track, an ironing head mounted on the carriage, a cam lever having its cam interposed between portions of the carriage and ironing head and operable at will for moving the head relatively to the carriage into pressing coaction with the buck, means for establishing a fulcrum connection between the cam and carriage about which the cam may be rocked in reverse directions when the head is in its pressing position, said cam having connection with the head for moving the latter in reverse directions during the reverse rocking movement of the cam about its fulcrum connection with the carriage.
11. In an ironing press, a buck, a track extending transversely of the buck and having a downwardly inclined portion at the rear of the buck, a carriage movable along said track and adapted to tilt rearwardly and downwardly when engaged with said downwardly inclined portion of the track, and a press-head mounted on the carriage to move therewith across the top of the buck and to tilt therewith when moved to the rear of the buck, and means for forcing the press-head into pressing coaction with the buck.
12. In a pressing machine, a buck, two substantially U-shaped members spaced apart and disposed with their leg portions substantially horizontal, one of the leg portions of each U-shaped member being below the buck and the other spaced above the buck, means connecting the U-shaped members for simultaneous movement, rollers on the U-shaped members to facilitate their sliding movement transversely of the buck, spring arms having one of their ends mounted on respective upper leg portions of the U-shaped members and extending forwardly from their mountings, a press head mounted on the front ends of said spring arms below the upper leg portions of the U-shaped members and movable with the connected U-shaped members to and from a position over the buck, and means for depressing the press head into pressing contact with the buck when registered therewith, against the supporting action of said spring arms.
13. In an ironing press, a buck, a track extending horizontally across the underside of the buck from front to rear thereof and having its rear end inclined downwardly, a carriage movable along the track and having an extension movable therewith across the top of the buck, a head mounted on the extension and means for moving the head into and out of pressing co-action with the buck.
14. In an ironing press, a buck, a U-shaped carriage having its opposite arms operatively extended respectively across the underside and top of the buck, a press head yieldingly mounted on said carriage below the upper arm thereof, and means between the head and overlying arm and cooperating therewith for forcing the head into pressing co-action with the buck.
15. In an ironing press, a buck, a U-shaped carriage having its opposite arms operatively extended respectively across the underside and top of the buck, a press-head movable toward and from the buck, springs on the carriage for supporting the head below the upper arm, and a cam plate between the head and upper arm and cooperating therewith for forcing the head into pressing co-action with the buck.
16. In an ironing press, a buck, a U-shaped carriage having its opposite arms operatively extended respectively across the underside and top of the buck, a press head between the buck and upper arm of the carriage, yielding connections between the carriage and head, and a cam between the top of the head and underside of the upper arm of the carriage operable at will for forcing the head into pressing co-action with the buck.
17. In an ironing press, a buck, a track extending transversely across the underside of the buck, a carriage movable along the track, means for fulcruming the carriage on the track for relative vertical tilting movement thereon, a press-head mounted on the carriage to move therewith across the top of the buck, and means for bringing the head and buck into pressing co-action.
18. In an ironing press, a buck, a track extending from the front side rearwardly across the underside of and beyond the rear edge of the buck and having its rear end inclined downwardly, a carriage movable along the track and extended upwardly and forwardly across the rear edge and top of the buck when in its forward position, leaf-springs secured at their rear ends to the rear portion of the carriage and extended forwardly therefrom, a press-head mounted on the front ends of the springs and movable with the carriage across the top of the buck, and a cam interposed between the head and adjacent portion of the carriage for moving the head toward the buck against the action of said springs, said carriage and head being adapted to tilt rearwardly and down-

wardly as the carriage rides along the downwardly inclined rear end of the track.

19. The combination with co-operative pressing elements of substantially equal

5 pressing area arranged one above the other, of a carriage slideable transversely of said elements and provided with spaced arms overhanging the upper element, separate springs on said arms for supporting said 10 upper element, and pressure-applying means operatively engaging both of said arms and the upper element for forcing the latter into pressing co-action with the lower element against the action of said springs.

15 20. The combination with co-operative pressing elements of substantially equal pressing area arranged one above the other, of a carriage slideable transversely of said elements, separate springs on said carriage con-

20 nected to the upper element in spaced relation for yieldingly supporting said upper element, and pressure-applying means co-operating with the carriage and upper pressing element for forcing the latter into pressing

25 co-action with the lower element against the action of the springs.

21. In an ironing press having a buck and an overlying press-head both elongated in one and the same direction, of a carriage slideable in the direction of the shorter axis of the buck and head and having a portion thereof overhanging the head, resilient connections between the carriage and head normally urging the head upwardly toward the overhanging

30 35 portion of the carriage, and pressure-applying means between the head and overlying portion of the carriage for forcing said head into pressing co-action with the buck.

22. In an ironing press, a buck, a press- 40 head, hand-operated slideable means for moving the head to and from a position directly over the buck, and a manually operated cam lever having its cam interposed between a portion of said slideable means and press-

45 head and movable in the direction of sliding movement of said slideable means for forcing the head into pressing co-action with the buck.

23. In an ironing press, a buck, a press- 50 head, a carriage for the press-head slideable by hand for moving the head to and from a position directly over the buck and provided with means normally urging the head upwardly, and a manually operated cam lever

55 having its cam interposed between a portion of the carriage and press-head and movable in the direction of movement of the sliding carriage for forcing the head downwardly against the lifting action of the first named 60 means into pressing co-action with the buck.

24. In an ironing press, a buck, a press- 65 head, a carriage for the press-head slideable by hand for moving the head to and from a position directly over the buck and pro-

vided with a pair of spring arms extending in the direction of movement of the carriage and normally urging the head upwardly, and means for forcing the head downwardly against the action of said spring arms.

25. In an ironing press, a buck, a press- 70 head, a carriage for the press-head slideable by hand for moving the head to and from a position directly over the buck and provided with a pair of arms overhanging the head, and a hand-operated cam-plate between both of said arms and the head and turnable from a substantially horizontal position to a substantially vertical position for forcing the head downwardly relatively to said arms.

26. In an ironing press, a buck member, a 80 U-shaped carriage having its opposite arms operatively extended respectively across the underside and top of the buck member, said carriage being movable in a horizontal plane toward and away from the buck member, a 85 press-head member carried by the carriage, and means for moving one of said members vertically relatively to the other member for performing the pressing operation.

27. In an ironing press, a buck member, a 90 track extending transversely of and across the underside of the buck member, a carriage movable along the track, an ironing head member carried by the carriage and adapted to overlie the buck member, and means for moving one of said members vertically into engagement with the other member.

28. In an ironing press, a buck member, a 95 track extending transversely of and across the underside of the buck member, a carriage movable along the track, an ironing head member carried by the carriage and adapted to overlie the buck, spring-means supporting one of said members and tending normally to move it away from the other of said members, and means for moving said spring-supported member vertically into engagement with the other member against the action of said spring means.

In witness whereof I have hereunto set my 100 hand this 10th day of May, 1929.

FRANK E. BAKER.
